UNITED STATES PATENT OFFICE.

CARL GRUNWALD, OF BREDENEY, GERMANY.

PUMPING APPARATUS.

1,189,096.

Specification of Letters Patent. Patented June 27, 1916.

Application filed April 18, 1911. Serial No. 621,963.

To all whom it may concern:

Be it known that I, CARL GRUNWALD, a subject of the Emperor of Germany, and residing at 116 Essenerstrasse, Bredeney, 5 Germany, have invented certain new and useful Improvements in Pumping Apparatus, of which the following is a specification.

This invention relates to that class of fuel 10 pumping apparatus for internal combustion engines in which a constant quantity of fuel, corresponding to the maximum requirement of the fuel pump, is conveyed continuously by means of a special supplying pump to 15 the suction chamber of the fuel pump, and the fuel supplied in excess flows away again through an overflow. Hitherto it has only been possible to carry out this method of fuel supply, when the highest level of the 20 fuel in the storage reservoir lay lower than the point of overflow in the suction chamber of the fuel pump.

Now the object of this invention is to provide a fuel pumping apparatus which shall 25 enable the aforesaid method of supplying the fuel to be carried out in any position of the storage reservoir.

A constructional example of the invention is shown in the drawing, in which—

30 Figure 1 shows diagrammatically partly in section and partly in elevation, those parts of a fuel pumping apparatus constructed according to this invention and with which this invention deals, and Fig. 35 2 shows in a sectional view and to a larger scale the special arrangement of a detail.

40 A is the cylinder of an internal combustion engine into which the fuel is sprayed, the fuel valve a^1 of which communicates with the fuel pump B, of well known construction, through the pipe C.

D is the compressed air vessel for the air for spraying in the fuel.

45 The suction chamber b^1 of the fuel pump B communicates through a fuel supply pipe E with a supplying pump F, which is constructed in the form of a rotary or fan pump and the supply pipe G of which is connected to a chamber h^1 of an overflow 50 reservoir H. The suction chamber b^1 of the fuel pump B is also directly connected to the overflow reservoir H by an overflow pipe J. The chamber h^1 of the overflow reservoir H is connected by means of a supply 55 pipe K, to the fuel storage reservoir L.

In the overflow reservoir H is arranged a float M, see Fig. 2, which is positively connected by a two-armed lever N to the spindle o^1 of a double acting valve. The valve disk O of this valve which is located in the chamber h^1 rests upon the mouth k^1 of the pipe K, which is made in the form of a valve seat, when the float M is in its highest position. When the float M is in its lowest position the valve disk O closes, with the upper surface of its disk, the passage h^2 between the chamber h^1 and the reservoir H the lower end of the passage h^2 being formed with a valve seat.

In the description of the action of the apparatus, it will be assumed that the overflow reservoir H is empty. Under these circumstances the float assumes, under the action of its own weight, its lowest position, while the valve O o^1 assumes its highest 75 position in which it lies against its upper seat h^2 . When the supplying pump F is set in operation it draws continuously a constant quantity of fuel, corresponding to the maximum requirement of the fuel 80 pump B, from the storage reservoir L through the pipe K, chamber h^1 and pipe G, and forces it through the pipe E to the suction chamber b^1 of the fuel pump B, the suction valve b^2 of which is acted on by the 85 governor of the engine (not shown) in the usual way, for the purpose of regulating the supply of fuel to the fuel valve a^1 to correspond to the load on the engine. When the fuel pump B draws less fuel from its suction chamber b^1 than the supplying pump 90 F supplies thereto, the excess of fuel flows through the overflow pipe J into the overflow reservoir H. When the level of the fuel in the overflow reservoir H has reached 95 a certain height due to the continuously less consumption of fuel by the engine, the further supply of fuel through the pipe J causes the float M to gradually rise and move the valve disk O from its upper seat h^2 . The 100 result of this is that the supplying pump F no longer draws the fuel exclusively from the storage reservoir L, but also from the overflow reservoir H simultaneously. If notwithstanding the level of the fuel continues to rise in the overflow reservoir H, the valve disk O approaches its lower seat k^1 more and more and finally shuts off the supply pipe K entirely. From this instant the supplying pump now continues to take the 110

fuel from the overflow reservoir H only. In consequence thereof the level of the fuel and with it the float M sink again, the supply pipe K being once more opened and fuel 5 again drawn from the storage reservoir L. The withdrawal of fuel from the storage reservoir L and the overflow reservoir H, is therefore automatically regulated by the 10 double acting valve according to the level of the fuel in the overflow reservoir H.

The above described arrangement enables the fuel storage reservoir L to be arranged at any desired point, *i. e.*, higher than the fuel pump B or below it, or, as is shown in 15 the drawing, to be so arranged that the level of the fuel in the storage reservoir may be higher when the reservoir is full, and on the other hand lower as it gradually becomes empty, than the point of overflow in the suc- 20 tion chamber of the fuel pump.

I claim:—

A fuel pumping apparatus for internal combustion engines, comprising a fuel storage tank, an overflow reservoir, a supply 25 pump running with a constant speed, a feed pump having a suction chamber, a fuel valve adjacent to the cylinder of the engine,

a source of compressed air communicating with said fuel valve and adapted to mix fuel and air and to spray the mixture into 30 said cylinder; a feed pipe between the valve and the suction chamber, a supply pipe from said supply pump to the suction chamber, a supply pipe from said overflow reservoir to the supply pump, a supply pipe 35 from said storage tank to the overflow reservoir, an overflow pipe from the suction chamber of the feed pump to said overflow reservoir and regulating means for cutting off the supply from said storage tank, comprising a float in said overflow reservoir, and a double acting supply valve actuated by said float and adapted to leave open one or the other or both the outlet from the storage tank and the outlet from the over- 40 flow reservoir.

The foregoing specification signed at Barmen, Germany, this 31st day of March, 1911.

CARL GRÜNWALD. [L. S.]

In presence of—

HERMANN ADOLPHS,

PETER REITZ.
